US00D767526S

(12) **United States Design Patent** (10) **Patent No.:** **US D767,526 S**
(45) **Date of Patent:** **** Sep. 27, 2016**

(54) **CELLULAR PHONE**

(71) Applicant: **LG Electronics Inc.**, Seoul (KR)

(72) Inventors: **Sanghyuck Lee**, Seoul (KR); **Seihyun Cho**, Seoul (KR)

(73) Assignee: **LG Electronics Inc.**, Seoul (KR)

(**) Term: **14 Years**

(21) Appl. No.: **29/509,443**

(22) Filed: **Nov. 18, 2014**

(30) **Foreign Application Priority Data**

Jun. 9, 2014 (KR) 30-2014-0028028

(51) **LOC (10) Cl.** **14-03**

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view of the cellular phone in an opened state;

FIG. 9 is a front view in an opened state thereof;

FIG. 10 is a rear view in an opened state thereof;

FIG. 11 is a left side view in an opened state thereof;

FIG. 12 is a right side view in an opened state thereof;

FIG. 13 is a top view in an opened state thereof; and,

FIG. 14 is a bottom view in an opened state thereof.

The broken lines shown in the drawings illustrate portions of the cellular phone that form no part of the claimed design.

1 Claim, 10 Drawing Sheets
